UNITED STATES PATENT OFFICE.

EDMUND O. SCHWEITZER, OF CHICAGO, ILLINOIS.

SELF-SETTING LIQUID FUSE.

1,358,180.

Specification of Letters Patent. Patented Nov. 9, 1920.

Application filed June 21, 1918. Serial No. 241,284.

To all whom it may concern:

Be it known that I, EDMUND O. SCHWEITZER, a citizen of the United States, residing at Chicago, in the county of Cook and State of Illinois, have invented a certain new and useful Improvement in Self-Setting Liquid Fuses, of which the following is a full, clear, concise, and exact description, reference being had to the accompanying drawings, forming a part of this specification.

My invention comprises a novel form of electrical apparatus termed by me a self setting liquid fuse.

This invention has been made to meet the demand for a device for relieving abnormal conditions of voltage on an electrical conductor. In electrical generation and distribution abnormal rises of voltage, surges of current oscillation and disturbances caused by switching and the like, as well as disturbances directly caused by atmospheric electricity, are all designated by the term lightning. There was a time in the history of the electrical art when atmospheric electricity was the chief and practically the only cause of disturbance on electric circuits. As soon as any considerable voltage was employed so that arcing would occur upon switching or a breakdown of the insulation, disturbances from the sudden making and breaking of the arc arose. The higher voltage coupled with a considerable current flow also brought out a peculiar electrical inertia effect which may be observed in some degree on all electric circuits. Many other factors such as switching of lines or transformers, starting of large pieces of apparatus and the like, also contribute to produce upon an electrical system abnormal conditions of voltage which may be of more or less danger to the system.

Numerous forms of apparatus for relieving such undesirable conditions have been proposed. They are all designated by the general term of lightning arresters.

Perhaps the one piece of apparatus that has found most favor in this country for high tension transmission is the electrolytic or aluminium cell arrester. The theory of this arrester has to do with the provision of

a conductor characterized by a relatively large current carrying capacity, but having a back electro-motive force substantially as great as the line voltage, so that all excess voltage will have a free path to earth, but the line voltage will be held back so that the dynamic electricity will be held on the line.

The theory of the electrolytic arrester is very nice, but as every engineer who has had to deal with the device knows, there are many practical difficulties which cause it to be far from an ideal arrester in practice.

One difficulty is the necessity for introducing a gap between the arrester and the line to prevent leakage of current and heating of the arrester. Another difficulty is the necessity of maintaining the gaseous film upon the plates. This is generally done by providing a charging resistance and a switch or contact usually at the horn gap for permitting a small current to be passed through the arrester periodically to recharge the same. This operation of recharging the arrester must be accomplished quite frequently to maintain the arrester in a workable condition. In case of repeated or heavy operation there is danger of heating the electrolytic arrester and causing a dissolution of the film on the plate. If this occurs, destruction of the arrester is practically certain.

Almost any arrester permits the excessive voltage to go from line to ground, but the difficulty is to prevent the dynamic current from following the path established by the potential discharge, and the flow of dynamic current must not be cut off too sharply otherwise disturbances are set up owing to the electrostatic capacity of the line.

I have conceived that if some means could be interposed in the line of the electrolytic arrester to make certain that the dynamic current would be positively but gradually interrupted upon the flow of a pre-determined amount of energy through the electrolytic arrester, the greatest operating danger of the electrolytic arrester would be eliminated.

My observations and experiments have led me to the conclusion that the ultimate cri-

terior of current flow is heat energy developed. To form a safeguard for preventing flow of current any apparatus to have maximum protective ability must depend upon 5 the heat developed to cause the breaking of the dynamic current flow.

The present invention aims to provide such a device.

I have found, however, that the device of 10 my invention being capable of eliminating the danger of faulty operation of the electrolytic arrester, is of such a capability as to serve in and of itself as a complete protective device without the electrolytic arrester.

15 I have conceived that if it were possible to take the dangerous potential in relatively small successive discharges closely following one another, a device of relatively small capacity would be able to handle a condition 20 of almost any size.

It is well known to those skilled in the art that the size or quantum of the disturbance cannot in any way be foretold. If the 25 arrester is made sensitive enough to take care of relatively small disturbances, it will generally be destroyed upon the first disturbance of greater amount. I have conceived that if the disturbance could be broken up into a number of disturbances of smaller 30 amounts, a protective device of small capacity and relatively great sensitiveness would be able to handle a disturbance of any size.

It is the object of my present invention 35 to provide a method of and means for accomplishing this result.

The particular means which I shall describe is but one of a great number of forms 40 in which the invention may be embodied. The means which I describe and illustrate in detail may operate in a number of different ways to accomplish the broad purpose. I shall set them forth in detail below.

It is well known that current flowing 45 through a conductor will be made manifest by its activity therein. For instance, in passing a given flow of current through a resistance, a pre-determined amount of energy in the form of heat energy will be liberated. This heat energy may do a pre-determined amount of work. Also the flow of a given amount of current through an electrolyte will release a certain amount of chemical energy which may also be put to 50 work. This energy which is developed by the flow of current, I employ in mechanically breaking the circuit to stop the flow of further current. That is to say, I provide an organization of parts such that after the pre-determined amount of disturbing current 55 has passed through the device, the circuit will be broken automatically. The organization is further provided for automatically re-making the circuit to let another pre-de-

termined amount pass out, and repeats until 65 the disturbance is quelled.

The energy developed or released may be in the form of heat or chemical activity. It is not advisable to develop the energy as magnetic energy because of the choking effect which such manifestation exerts upon the quick release or discharge of the disturbance and the consequent counter-disturbance which may be created. I have observed that the development of heat or chemical energy 70 does not appear in any way to slow down or 75 pervert immediate relief.

There are two general conditions which 80 may employ my device to advantage. The first condition is where a certain quantity of current is to be discharged and repeated operation of the device is necessary to permit of such discharge. Under these circumstances the device of my invention assumes the aspect of a controlling device for breaking up the disturbance into parts and separately discharging the parts. In view of 85 this aspect of the invention, I often term the same an electro-thermal valve.

Under the condition which would exist 90 where the amount of current or disturbance to be discharged is no greater than that which is dependent upon the constants of the line and which can be conducted or discharged by the device before the same operates to break the circuit, a different theory 95 of action becomes more prominent. In this aspect of the invention the discharge is completed substantially instantly. The apparatus then functions to cut off the power current gradually enough to prevent disturbances. The automatic reestablishment of the 100 circuit then becomes important in preparing the device for the next operation. Under these conditions the device assumes the characteristics which make it valuable as a self setting fuse.

In one form of my invention which I have successfully operated, I provide a U-shaped receptacle for liquid of a relatively low conductivity such as water with a small amount of conducting material in solution. The legs of the U are of unequal length. One leg of the U, namely the longer, is open to atmosphere. The shorter leg is closed at its upper end to form an electrode chamber. An electrode projects into the top of the chamber normally in contact with the surface of the liquid, and a second electrode projects into the chamber below the level of the liquid at a predetermined distance below the first electrode. The resistance of the liquid or the vapor and liquid between the two electrodes determines the rate at which electrical energy may pass from the line or other conductor to be protected, to ground or other conductor. 110 115 120 125

The invention is not limited to lightning

protection only, as it may be employed to govern the rate of current flow between two points for any other purpose. I consider the device particularly adapted for interrupting the flow of high tension current, but do not intend to limit the invention to such use. It is to be understood further that while I employ preferably a single unit, I do not intend to be limited to a single unit, but may employ a battery of the same either in series or in parallel, or both.

One of the most desirable features of a lightning arrester and one which has not heretofore been feasible is the ability to be connected directly to the line. By providing a small gap between the liquid and the upper electrode as by maintaining the level lower than the top electrode, I am able to connect the present device directly to the line.

In the accompanying drawings which form a part of the present specification, I have illustrated a particular embodiment of my invention which will teach those skilled in the art how to construct and operate the invention.

Figure 1 is a diagrammatic layout of my invention employed in connection with an electrolytic arrester;

Fig. 2 is a similar diagram of an embodiment showing the complete lightning arrester;

Fig. 3 is an enlarged sectional view of the device of my invention showing the electrodes and the interior of the gaseous chamber;

Fig. 4 is a diagram showing two of the devices employed in series;

Fig. 5 is an embodiment of the invention showing a series of cells forming a modified form of arrester; and.

Fig. 6 is a series of performance curves on various voltages.

Fig. 7 is a plan bottom view of the upper electrode.

In Fig. 1 I have shown the device of my invention as connected between the horn gap 2 and the electrolytic arrester 3 for protecting the transmission line 1.

The horn gap 2 may be of any preferred type and as shown, consists of the horn electrodes 4 and 5 mounted upon a suitable supporting base 6, this base being constructed of insulation or being suitably insulated as by means of the insulator 7. The horn gap 2 is provided with a contact finger 8 for bridging the gap to permit current to flow through the charging resistance 9 to charge the electrolytic arrester 3, as is well understood by those skilled in the art.

The horn electrode 5 is connected by means of the conductor 10 to the line wire 1 and the electrode 4 is connected through a flexible conductor 11 to the stem 12 which forms one terminal of the self setting liquid fuse

or electro-thermal valve of my invention, which is broadly designated by the reference numeral 14.

The detailed construction of the self setting fuse 14 is shown in Fig. 3. A sleeve 70 of bakelite or other suitable insulation as shown at 15, is provided with the upper and lower caps 16 and 17 respectively, these caps being preferably metallic caps such, for instance, as pipe caps. The bakelite sleeve 15 is cemented at its ends into the caps 16 and 17 as indicated at 18, to form a closed chamber.

The closed chamber 19 contains the two electrodes 20 and 21, the upper electrode 80 comprising a pyramidal block of graphite which is secured upon the stem 12 which in turn is connected as previously indicated, to the horn gap electrode 4.

The stem 12 passes out through a stuffing box 22 formed in the nipple 23. The nipple 23 is connected through suitable reducers 24 and 25, to a coupling or nipple 26 which is mounted on the cap 16. The stuffing box 22 is provided with a gland 27 and a foil 90 lower 28 for maintaining a fluid tight joint between the stem, 12 and the interior of the chamber 19. The coupling or nipple 26 forms a small chamber 29 in communication with the chamber 19 for the collection of 95 vapors or a gaseous medium which is evolved upon operation of the device as will be described later. The chamber 29 is provided with a discharge pipe 30 which has a nozzle 31 controlled by a needle valve 32. 100 The purpose of this pipe, valve and nozzle is to permit vapors or a gaseous medium to be dissipated or discharged from the chamber 29 at a pre-determined rate.

The lower electrode 21 comprises a disk 105 of graphite mounted upon a metallic stem 33 which stem is connected as by being screw-threaded to the metallic cap 17. The metallic cap 17 is connected to ground as by means of the conductor 34 or the same 110 may be accomplished by the metallic framework upon which the device may be mounted.

The chamber 19 at its lower end communicates with a pipe 35 which is threaded into 115 an opening through the lower cap 17, this pipe communicating by way of the T 36 with a horizontal pipe 37. The horizontal pipe connects with a vertical pipe 38, which opens at its upper end into a storage chamber 39 which in this case is formed by a larger piece of pipe communicating with atmosphere by the valve 60. The purpose of the chamber 39 is to receive the fluid which is discharged from the chamber 19. 120 A controlling valve or a check-valve with a by-pass may be interposed in the pipe connecting the chamber 19 with the chamber 39 for controlling the discharge of fluid to and from the chamber 39.

While I describe the storage leg of the U as open to atmosphere, it is not essential, as a closed chamber could be used under proper conditions.

5 The operation of the device as illustrated in Figs. 1 and 3 will now be understood from the following.

In case of a disturbance arising on the line 1 of sufficient voltage to break down 10 the gap between the horn electrodes 4 and 5, it is desirable to provide a convenient path to ground, of such a character as to relieve the disturbance quickly but to positively break the flow of current in a smooth cycle 15 to prevent potential rises after a predetermined quantity has passed therethrough or after a given time interval.

The chamber 19 is normally filled with 20 water to a point slightly below the discharge nozzle 31. The liquid will normally stand at the same level in both legs of the U-shaped container. The liquid which I have heretofore employed is common city water taken from the tap in the city of Chicago. 25 Other liquid might well be used, as will be apparent from the requirements under which this particular liquid is employed.

Current flowing from the line wire 1 across 30 the horn gap 2 is conducted through the stem 12 and the electrode 20 through the body of liquid between the electrodes 20 and 21, and from thence to ground.

The resistance of this path is relatively 35 high but as it is free of inductance and is of relatively large capacity, if the disturbance upon the line 1 is not of a sustained character, the discharge to earth will be quick and easy. The flow of dynamic current which tends to follow the flow of potential 40 must always be positively interrupted, otherwise a continuous loss would occur, and in the circuit indicated in Fig. 1, the electrolytic arrester 3 would become heated up, and become ineffective if no positive interruption of the dynamic current were secured. The horn gap 2 is normally sufficient to accomplish this, but under certain circumstances the horn gap is insufficient protection.

50 With my device in series with the horn gap and the ground connection whether including the electrolytic arrester or not, the passage of current through the liquid 40 causes the same to be vaporized so that a body of vapor is trapped in the chamber 29 and as the current flow heats up the liquid, causing more rapid generation of vapor, the liquid will be forced down below the electrode 20, breaking the circuit completely 55 between the electrode 20 and the liquid by the interposition of the steam or other gaseous medium which is generated.

The discharge nozzle 31 which communicates with the chamber 29 governs the rate

at which the pressure is dissipated so as to 65 control the time interval during which sufficient pressure will be generated to break the circuit. The valve 32 thus becomes the means for regulating the device for controlling the rate at which current may flow 70 through the device. The creation of a pressure of vapor or gaseous medium in the chamber 29 will force the liquid down through the pipes 35, 37 and 38, into the receiving chamber 39 where the liquid is 75 stored up. When the circuit has been broken, the liquid will tend to flow back by gravity to close the circuit between the electrodes 20 and 21 as fast as the pressure escapes by way of the nozzle 31.

80 The capacity of the device may be varied by varying the amount of impurity in the water 40, or by substituting other liquids or mixtures of liquids. Numerous other factors may be varied to change either the rate at which pressure is built up to drive the liquid out from between the electrodes or the rate at which current may pass through the device. The distance between the electrodes 20 and 21 may be varied by moving 85 the stem 12, and for this purpose the stem 12 has been provided with graduations as indicated at 41, so that accurate knowledge may be had of the distance between said electrodes.

95 In case of a discharge of greater quantity than the immediate capacity of the device of my invention, several successive operations of the device would occur. That is, upon the first flow of current, pressure 100 would be generated in the chambers 19-29, the liquid would be forced out of the chamber 19, breaking the circuit between the electrodes 20 and 21, and thereafter the escape of pressure by way of the nozzle 31 would 105 permit re-closing of the circuit and repeated operation until the disturbance would be relieved.

110 It is found by experiment that the rate at which the device operates depends upon the temperature of the apparatus and the liquid, the condition being such normally that a greater period of time is permitted for the first amount of discharge than will be permitted for the successive charges, thereby tending to give instant relief but to control successive discharges so that the device always maintains positive control over the rate discharge.

115 The vaporization of the liquid gives a 120 non-conducting gaseous body in the upper part of the chamber which may consist in part of the gases formed by the dissociation of the water. In any event, the gaseous medium which is thus generated is of a non-conducting character at least far below the conductivity of the water itself, so that the 125 tendency is to interpose a non-conducting

medium where a conducting medium was formerly present. The pressure and the non-conductivity of the gaseous medium tend to extinguish the arc very promptly 5 and without any deleterious effect upon the electrode 20. I have observed that after a great number of operations of the device the graphite electrode 20 is not pitted or attacked in any manner. In order to avoid 10 the use of a horngap the level of the liquid 40 may stand normally below the upper electrode. Thus the gap will appear inside of the sleeve 15 between the electrode 20 and the liquid 40, and the device may be connected 15 directly to the line.

In this condition the space at the top of the chamber 19 is normally full of vapor and the device stands ready to permit of a discharge of over potential at any time. 20 In case the vapor should tend to dissipate, a small leakage current would tend to establish itself and would reform the jacket of vapor. Thus the device would be constantly ready for instant action and the lag 25 of the heating effect would be considerably cut down.

In Fig. 2 I have illustrated my invention as forming the sole protective means for the line 1 without the electrolytic arrester 30 shown in Fig. 1. The operation of the device is the same as previously indicated. The adjustments for different voltages and capacities are obvious from the above discussion.

In Fig. 4 I have indicated the manner in which a pair of these fuses may be connected in series to operate simultaneously. In this case the two devices are connected electrically in series as indicated in the figure 6 by means of the conductors 43, 44 and 45, between the horngap 2 and ground. The upper ends of the liquid containing chambers are connected together by means of the pipe 46. A common control valve 42 for 45 governing the rate of permitting the escape of the gaseous medium, is connected to the pipe 46, and this valve 42 insures operation of the devices in unison.

The chambers 39 which are made of 50 sleeves or tubes of insulating material such as fiber are connected together by a pipe 62 and this pipe communicates with atmosphere through the valve 61.

The detailed operation will be apparent 55 from the foregoing description of a single form of the invention.

In Fig. 5 I have indicated the manner in which a series of cells embodying my invention may be compactly arranged in a 60 single casing 48 and controlled by a common discharge valve 49 for governing the rate at which the circuit is broken. A series of inverted cups or cones 50 which are made of insulation, are mounted upon a central tube

51 which is also preferably made of insulation or of insulated sections, this tube having openings 52 communicating with the upper end of each conical cup or shell 50. These openings permit of the escape of pressure from under each shell 50 into the common pipe 51, and out of the common valve 49, so that all of the cells will operate at a uniform rate. A series of graphite electrodes 54 are fixed in the walls of the shells or cones 50 so that their tapered lower ends 75 will give increasing resistance to the flow of current as the level in each cell is forced downward.

The operation of this form of the device will be apparent. Steam or other gaseous 80 fluid will be generated and will collect at the top part of each cell, thereby forcing the liquid away from the particular electrodes 54 and tending to increase the resistance to the passage of current at each 85 cell and thereby controlling the amount of current flow. The expansion of the steam or other gaseous medium will force the liquid away from contact with the electrodes 54 and will positively break the current at 90 each point. After this occurs the gaseous medium will be dissipated at the valve 49 and the circuit remade. Thus the operation is identical with the operation described in connection with Figs. 1 and 3. 95

I have found that when the resistance of the liquid 40 and the vapor above it is kept relatively high, the device may be connected directly to the line without the use of the gap 2. However, I interpose the horngap 2 100 when the liquid connects the electrodes 20 and 21 as this avoids the constant loss which would otherwise occur. I have employed a thin layer of oil upon the top of the body of water 40. This prevents unduly rapid 105 evaporation and also acts as a non-conductor which is interposed between the upper electrode 20 and the surface of the water.

Where the surface of the water 40 is maintained below the upper electrode 20 the vapor space between the electrode and the water seems to become ionized and very sensitive to rises in voltage permitting a quick discharge. The resultant evolution of fresh vapor by the dynamic current breaks down 115 the condition and causes interruption of the current flow.

The body of vapor may be maintained in sensitive condition by a separate heater in the chamber 39. 120

Fig. 6 indicates the performance of the device of my invention during tests made upon various voltages. While the curves seem to indicate abrupt breaking of the current flow, this is due to the scale upon which the curves 125 are drawn and as is shown upon the field of the oscillograph, the break is not sudden but relatively gradual and no oscillations or

surges are induced. A curve drawn through the peaks of the current flow curves takes the form of a rectangular hyperbola.

I am aware that water columns or sprays 5 have been employed particularly in England for the discharge of potential from transmission lines and the like. However, I am laying no claim to such construction or method of operation. I consider that my invention 10 is entitled to a broad construction, and do not intend to limit the same except as may be set out in the appended claims.

I claim:

1. The method of breaking the flow of current through a liquid which comprises conducting the current through the liquid at a rate sufficient to vaporize a part of the liquid, then causing the vapor to accumulate and displace a portion of the liquid to break the 20 continuity of the current flow independently of the rate of generation of said vapor.

2. The method of interrupting the flow of current in a liquid conductor which comprises vaporizing a part of the liquid conductor by the heat of the current flow, then causing the vapor so generated to be accumulated and to exert a pressure upon a free surface of the liquid conductor to move the same down and out of conducting relation.

3. The method of periodically interrupting a flow of current through a liquid conductor which comprises causing the flow of current to vaporize a portion of the liquid conductor, then accumulating the vapor and causing the vapor to move a portion of said liquid conductor down and out of conducting relation, then dissipating the vapor to permit the conductor to return to conducting relation.

4. The method of interrupting the flow of current through a liquid which comprises causing the current through the liquid to generate a non-conducting gaseous medium, accumulating said gaseous medium under pressure above the surface of the liquid, then moving the liquid by said gaseous pressure down and out of conducting relation to break the current flow.

5. In a current interrupting device, a pair 50 of electrodes and a conducting liquid between them, said liquid being adapted to evolve a relatively non-conducting gaseous medium upon the passage of current therethrough and means for trapping the gaseous medium above the free surface of the liquid one of said electrodes being arranged near the normal surface of the liquid and adapted to lose contact with the liquid when the gaseous medium is formed and trapped.

6. In a current interrupting device, a 60 chamber, an electrode adjacent the upper end of the chamber, an electrode adjacent the lower end of the chamber, and a conducting liquid between said electrodes said chamber forming a closed trap for trapping vapor

above the free surface of the liquid, a relatively large outlet for liquid at the lower part of the chamber and a relatively small outlet for vapor at the upper part of said chamber.

7. In a current interrupting device, a pair 70 of electrodes, and a conducting liquid between them, said liquid being adapted to evolve by the flow of current between said electrodes a relatively non-conducting gaseous medium under pressure for displacing the liquid between the electrodes and a trap for trapping the gaseous medium above the free surface of the liquid.

8. In a current interrupting device, a pair 80 of electrodes, a conducting liquid between them, said liquid being adapted to evolve a substantially non-conducting vapor upon the passage of current through the same, and means to trap said vapor above the normal surface of the liquid and to displace the liquid.

9. In a current interrupting device, a pair 90 of electrodes, a conducting liquid between them, said liquid being adapted to evolve a relatively non-conducting vapor for displacing the liquid between the electrodes, and means governing the dissipation of said vapor.

10. In combination, a U-shaped passage-way having a closed chamber at the top of one leg and a chamber at the top of the other leg, an electrode in the upper end of the closed chamber, a body of liquid of low conductivity in said closed chamber and in 100 said U-shaped conduit, an electrode for the lower end of said closed chamber, means for adjusting the upper electrode, and means for controlling the rate of discharging liquid from said closed chamber.

11. In combination, a closed chamber having an upper and a lower electrode, a body of liquid of low conductivity between said electrodes, an atmospheric leg communicating with said closed chamber, said leg being 110 adapted to receive the liquid discharged from the closed chamber when a pressure is created therein.

12. In combination, a sleeve of insulation, a metallic cap at each end of the sleeve, a 115 bushing in the cap at the upper end of the sleeve, a rod passing through said bushing, a stuffing box for the rod, an electrode on the inner end of said rod, an electrode mounted on the lower metallic cap, and an 120 atmospheric connection for receiving fluid discharged from the sleeve communicating with the interior of the sleeve through the lower cap.

13. In combination, a sleeve of insulation, 125 a metallic cap at each end of the sleeve, a bushing in the cap at the upper end of the sleeve, a rod passing through said bushing, a stuffing box for the rod, an electrode on the inner end of said rod, an electrode on 130

5 mounted on the lower metallic cap, an atmospheric connection for receiving fluid discharged from the sleeve communicating with the interior of the sleeve through the lower cap, and a valve governing the escape of fluid from the upper end of the sleeve.

14. The method of interrupting a flow of current from an electrode through a liquid conductor which comprises vaporizing a 10 part of the liquid by the flow of current, trapping the vapor so evolved above the surface of the liquid and moving the liquid out of conducting relation by the pressure of vapor thereupon.

15. The method of relieving an electrical disturbance which comprises conducting a flow of current from an electrode through a liquid conductor, generating a vapor from the liquid by said flow, and causing said 20 vapor to press upon the free surface of the liquid to move the level of the liquid conductor downward far enough below the electrode to break the flow of current.

16. In combination, a liquid container, a 25 body of liquid therein, an electrode normally extending below the free surface of the liquid, and connections for causing a flow of current from the electrode through the liquid, said flow of current being adapted to generate a gaseous medium which rises 30 through the liquid, said container having a closed top forming a gas or vapor accumulator above the level of the liquid for accumulating said gaseous medium independently of the rate of flow of current until sufficient pressure is accumulated above the 35 free surface of the liquid to separate the liquid and the electrode.

17. In a device of the class described, a 40 pair of chambers communicating with each other at their lower ends, an electrode in one chamber, a liquid standing normally high enough in both chambers to contact with the electrode, said one chamber having a closed top to trap vapors and a vent for 45 permitting the dispersion of vapors from said one chamber.

18. In combination, a pair of chambers connected together at their lower ends, one 50 of said chambers being of greater capacity than the other, an adjustable electrode in the smaller chamber, a body of liquid in said chambers, said smaller chamber having a closed top for trapping vapor freed by the 55 passage of current from said electrode through said liquid, and means for dissipating the vapor trapped in said smaller chamber.

19. In combination, an electrical line, a 60 pair of chambers connected together at their lower ends, one of said chambers being of greater capacity than the other, an adjustable electrode in the smaller chamber, a body of liquid in said smaller chamber, said 65 smaller chamber having a closed top for

trapping vapor freed by the passage of current from said electrode through said liquid, and a normally open connection between the electrode and the line.

20. The method of interrupting a flow of 70 current which comprises passing the current from an electrode through a liquid, generating a predetermined quantity of vapor for each unit of current flow, accumulating and trapping the vapor above the free surface of the liquid about the electrode and progressively forcing the liquid down below and out of contact with the electrode by said accumulated vapor, the pressure of said gaseous medium serving to separate 80 said conducting liquid and said electrode from each other.

21. In combination, an electrode, a liquid 85 normally in contact with the electrode, a liquid container having a vapor trap at its upper end and means controlling the rate at which the vapor may escape from said trap, the pressure in the vapor trap controlling the separation of the electrode and the liquid.

22. In combination, an electrode, a body 90 of water normally in contact with the electrode, a tank having a vapor trap at its upper end, said tank containing said electrode, and a vent having a valve for controlling the rate at which vapor may escape from said trap, the pressure of the vapor in said trap controlling the separation of the liquid and the electrode.

23. In combination, a pair of tanks closed 100 at their upper ends and communicating with each other at their lower ends, a liquid having a free surface in each tank, an electrode in one tank normally in contact with the liquid and a vent for said one tank for dissipating vapor trapped in the top of said tank, the pressure of the vapor trapped in the top of said tank controlling the separation of the liquid and the electrode.

24. In combination, a liquid container 110 having a closed top forming a vapor trap, a body of water in said container, an electrode projecting through the container into contact with the water, said electrode being insulated from the container, a liquid outlet 115 in the bottom of the container and a layer of oil on the free surface of the body of water.

25. In combination, a tank having a trap 120 for vapor at its upper end and an outlet for liquid at its lower end, a body of conducting liquid in said tank having a free surface, an electrode projecting through the top of the tank into contact with said body of liquid, said liquid being a conductor, and 125 a layer of insulating liquid overlying said free surface of the body of liquid.

26. In a device of the class described, a closed chamber having in its upper portion 130 a trap for vapor and adapted to hold a

liquid in its lower portion, said chamber having an outlet communicating with the lower portion, and electrode means in the chamber for generating a vapor from the liquid, said electrode means comprising an upper electrode positioned within the liquid so that trapping of the vapor will drive the

liquid down below said electrode and another electrode at all times in contact with the liquid.

10

In witness whereof I hereunto subscribe my name this 17th day of June A. D. 1908.

EDMUND O. SCHWEITZER.
